INVENTOR

Charles G. Palmer
BY
Frederick C. Fischer
ATTORNEY

UNITED STATES PATENT OFFICE.

CHARLES G. PALMER, OF NEWARK, NEW JERSEY.

SOCKET WRENCH.

Application filed December 15, 1921. Serial No. 522,506.

To all whom it may concern:

Be it known that I, CHARLES G. PALMER, a citizen of the United States, residing in Newark, in the county of Essex and State of New Jersey, have invented certain new and useful Improvements in Socket Wrenches, of which the following is a specification.

The principal purpose of this invention is 10 to produce a wrench, of the fixed socket type, in which a plurality of reversible heads, each having two unlike openings, are interchangeably engageable with a single operating bar.

Another important object is to provide 15 storage mounting means for such of the heads as are not in operative position whereby any selected head is instantly accessible for use.

A further purpose is in the provision of 20 simple but effective means for retaining a selected head in operative position on the wrench handle bar, similar means also being used in preventing the remaining heads 25 from becoming displaced.

These and other objects, such as convenience, strength, simplicity and economy in construction, are secured by the novel construction and combination of parts here- 30 after fully described and clearly shown in the accompanying drawing, forming a material part of this disclosure, and in which:—

Figure 1 is a perspective view of a wrench 35 showing an embodiment of the invention, one of the heads being in operative position and shown in longitudinal section to disclose its construction.

Figure 2 is an enlarged fragmentary plan 40 view of the same looking from the engaging side.

The handle bar, designated in the drawing by the numeral 5, is formed with a relatively short right angle extension 6 at one 45 end, from bar steel of uniform hexagonal cross section, both end surfaces being finished flat and square across.

Adjacent the end surface 6', of the bent portion of the bar, is a shallow annular 50 groove 7 having a semi-circular concave bottom and adapted to loosely confine a spring metal ring 8 having an opening 8' between its adjacent ends which permit contraction of the ring within the groove, while normally the periphery of the ring extends

slightly outward beyond the flat longitudinal surfaces of the hexagonal bar.

A similar groove 9 is formed adjacent to the end 5' of the handle bar and fitted to it, in a like manner, is a corresponding 60 spring ring 10 having a spaced end opening 10'.

The wrench heads, three of which are shown, respectively 11, 12 and 13 are each essentially cylinders of varying diameter 65 and length as best suited to the sizes of the socket opening contained in their respective ends, both of which are fitted to receive and neatly engage nuts, bolt heads, etc., in turning the same, the articles being variable in 70 sizes, proportions and cross sections.

As an illustration, the head 11 is seen to have a hexagonal socket 14 in one end and a slightly larger socket 15 in its opposite and operatively disposed end. 75

Disposed midway between the socket openings is a web 16 having a central hexagonal through opening 17 fitting the handle bar element 6 and also capable of sliding over the main, straight portion 5 of the bar, and it is to be understood that each of the several socket heads are duplicates with respect to the web 16 and opening 17. 80

From the foregoing it will be apparent that upon entering the bar element 6 through 85 either end of any of the socket heads, the extending portions 6' will, by proper manipulation of the bar and head respectively, find its way into the axial opening 17 and upon applying sufficient pressure, cause 90 the curved contacting periphery of the ring 8 to contract, thus preventing retraction and consequent separation of the parts until considerable force is exerted.

In order to avoid having the end 6 of the handle bar project unduly into the sockets disposed for operative engagement with an article, detent lugs 18 extend integrally out from opposed points on the bent portion 6 of the handle bar to engage the adjacent 100 surface of the web 16, these detents being so located as to permit the spring ring 8 to properly function, thus preventing respective longitudinal movement.

It will be seen that the socket heads, not in actual use, can be readily slipped over the retaining spring ring 10 at the outer, straight end of the bar 5 and when so mounted are held in a convenient manner, safe 105 from loss and instantly accessible at will. 110

While certain preferred embodiments of this device have been shown and described, it will be understood that changes in the form, arrangements, proportions, sizes and details thereof may be made without departing from the scope of the invention as defined in the appended claims.

Having thus described my invention, what I claim as new and desire to secure by Letters Patent, is—

1. A wrench comprising an angled handle bar of uniform cross section, a reversible socket head having unlike sockets in each end, a web in said socket intermediate said end sockets, said web having an opening engageable with said bar, and means at each end of said bar for retaining said head thereon.

2. A wrench comprising an angled handle bar of uniform cross section, a reversible socket head having unlike sockets in each end, means interjacent said sockets engageable with said bar, and spring detents carried by said bar for securing said heads upon either the straight or angled portion of said bar.

3. A wrench comprising a hexagonal bar having an angular projection said projection having a shallow annular groove adjacent its end, a double ended socket head, a transverse web in said head intermediate said sockets fitted to receive said projection, and a single spring ring carried in said groove, said ring being suited to pass through the opening in said web and engage the side opposite said bar.

4. A wrench comprising a bar of polygonal cross section, a short angular extension at one end thereof, said extension having an annular groove near its end, a split ring

loosely contained in said groove, a cylindrical head having unlike sockets in each end, a transverse web intermediate said sockets, said web having an opening suited to receive said extension and permit the forced passage of said ring, and detent lugs integral with said extension adapted to contact with said web limiting the position of said ring with respect to the web.

5. A wrench comprising a bar of polygonal cross section, a short angular extension at one end thereof, annular grooves near the ends of said bar and its extension, detents on said extension spaced definitely from the ring carried thereby, a reversible socket head having unlike sockets in their opposite ends, and webs in said heads having openings receptive of said bar, said webs being uniformly equivalent in thickness to the distance between said detents and adjacent ring.

6. A wrench comprising a bar having polygonal sides, an angular extension at one end, stops on said extension, a double ended socket head having a central part suited to receive said bar or its extension, spring means carried by said extension adapted to engage one side of said part to maintain the other side of the part in contact with said stops whereby said head is held in operative position, and a like spring means on the straight end of said bar adapted to maintain the head thereon when in inoperative position.

This specification, signed and witnessed this 14th day of December, 1921.

CHARLES G. PALMER.
